REUBEN STANLEY SMITH, OF MILWAUKEE, WISCONSIN.

PROCESS FOR MAKING CURVED FLANGED BARS.

1,356,567.

Specification of Letters Patent. Patented Oct. 26, 1920.

Application filed April 15, 1920. Serial No. 374,174.

To all whom it may concern:

Be it known that I, REUBEN STANLEY SMITH, a citizen of the United States, residing in the city of Milwaukee, in the 5 county of Milwaukee and State of Wisconsin, have invented certain new and useful Improvements in Processes for Making Curved Flanged Bars, (Case #154;) and I do hereby declare the following to be a full, 10 clear, and exact description thereof, such as will enable persons skilled in the art to which the invention pertains to use the same, reference being had to the drawings hereto attached for disclosure as to certain 15 details of the manner in which the invention is reduced to practice.

My invention relates to improvements in processes of shaping sheet metal blanks, particular reference being made to that 20 class of operations in which the side margins of a curved blank are bent so as to stand in parallel planes which are normal to the plane of the central portion or web of the blank, to form a channel bar. The invention is primarily designed for use in the 25 production of side bars and cross bars of automobile or other vehicle frames. While I have chosen to illustrate and describe my invention as applicable to the production of 30 a cross bar blank for an automobile frame, it will be understood that this particular application has been selected as a mere conventional exposition of the invention, and that the latter is not to be limited in its 35 application to the production of such cross bars, but may also be applied to the production of side bars of automobile frames, as well as to the production of curved channel bars intended for other uses.

40 The invention herein disclosed embodies in its broader aspects the process for making curved flanged bars covered by my application, Serial No. 288,085, filed April 5, 1919, since then matured into Patent #1,343,647, 45 dated June 15, 1920, to which reference may be had for disclosure of the invention in some of the more specific forms of its application.

The present invention is applicable in 50 particular to flat sheet metal blanks of curved outline, but the manner of producing such curved blanks is not material to the purposes of my said invention. As a matter of fact, such curved blanks may be 55 punched from wide rectangular plates, or they may be punched from comparatively

narrow rectangular plates, which have been bent edgewise or in the direction of their width. The first mentioned method of producing curved blanks from wide rectangular plates is very wasteful, and I prefer, as a matter of economy, to resort to the more modern method of bending a comparatively narrow rectangular plate edgewise, so as to present an irregular area from which the 60 curved blank to form the channel bar may be punched, without the waste incident to the former methods.

The curved blanks produced by either of the practices outlined above, are fed to a 70 drawing press of usual type, the dies of which act to turn the side margins from the plane of the blank into parallel planes standing normal to the plane of the central portion or web of the blank. In such drawing operation, the length of the marginal sections forming the convex portions of the flanges of the bar is contracted, with the result that each of such marginal sections is thickened throughout its extent. Conversely, the length of the marginal sections forming the concave portions is expanded longitudinally, with the result that such portion is unduly stretched, thereby producing a weakness and sometimes tearing the 85 blank by reason of an uneven molecular displacement of the material of which the blank is formed.

It is the purpose of my present invention to crimp or corrugate the side margins of 90 the curved blank at the points where the concave flanges are to be formed, so that the molecular displacement occurring in the concave margin when the latter is turned will be evenly distributed throughout the 95 length thereof, and will present a surplus of material which will compensate the expansion which takes place in the drawing operation. This provision of additional material in the portions of the flanges which are concaved, will permit such flanges to be turned to their perpendicular positions with reference to the plane of the blank, without exerting a tearing strain at any point. Thus, when the concave margins of the 100 curved blank are subjected to the drawing operation, the material at those points will stretch evenly throughout the crimped or corrugated area, so that structural weakness in the channel bar is avoided.

110 In the drawing operation, the lateral pressure exerted upon the corrugated mar-

gins by the side walls of the matrix as the punch forces the blank into the matrix, will serve to smooth out such marginal corrugations.

5 In the drawing which forms a part of this specification,

Figure 1 is a perspective view of a cross bar forming one of the constituent elements of an automobile frame, it being understood

10 that the selected illustration is merely to show the application of my invention to the production of curved flanged bars.

Fig. 2 is an end view, or it may be a cross sectional view at any given point, of the structure as shown in Fig. 1, this view showing also in dotted lines the side margins of the blank as lying in the plane of the blank, from which they are turned in the drawing operation to form the flanges of the bar.

20 Fig. 3 is a plan view of a curved blank, from which the cross bar of Figs. 1 and 2 is formed, this view illustrating my method of crimping the margins of the blank at those portions where the concave flanges are 25 to be formed.

Fig. 4 is a view in elevation showing a portion of the concave edge of the blank, and looking in the direction of the arrow 4 in Fig. 3.

30 Fig. 5 is a cross section on the line 5—5, Fig. 3, the line cutting the concave margins at opposite sides of the blank and showing the displacement caused by crimping.

Fig. 6 is a cross section on the line 6—6, Fig. 3.

Referring to the drawings, Fig. 1 illustrates in perspective a conventional cross bar 1, composed of a vertical web 2 and top and bottom flanges 3 and 4, respectively.

40 The top flange comprises plain end portions 5, convex portion 6 and a plurality of concave portions 7. The bottom flange 4, parallel through its length with the flange 3, is composed of plain end portions corresponding 45 to the portions 5 of the top flange, a concave portion 8 and a plurality of convex portions 9. The curved blank 10, Fig. 3, is adapted to have its margins 11 and 12 folded along the dotted lines 11¹ and 12¹, so 50 as to form the reinforcing flanges of the channel bar.

The areas indicated, 7¹ 7¹, and 8¹, in Fig. 3 form the concave portions 7, 7, and 8, respectively, of the completed cross bar. The

55 areas 7¹ 7¹, and 8¹, are crimped or corrugated by the action of suitable dies in a stamping press, so that the effect of the operation of the press is to transform the concave margins of the curved blank from the flat plane of the blank into corrugated surfaces, such as is indicated in Fig. 4.

In connection with the concave edge 8 of the cross bar, I have indicated in Fig. 3 the extent of the molecular displacement which

60 65 occurs when the margin of the blank form-

ing such concave edge is turned into a plane which is normal with respect to the plane of the blank. The dotted line 13 in Fig. 3 indicates the normal length of the concave edge of the curved blank, and the dotted line 14 in the same figure indicates the length of the edge of the concave flange after it has been turned from the plane of the blank.

By means of this comparison, it will be seen that the metal of the concave margin in being turned, must be expanded in a considerable degree, and that unless the strain is evenly distributed over the whole of the area, the material is apt to tear at its weakest point, or at least be so strained as to be liable to fracture.

The dies of the press which crimp the margins of the curved blank at the points where the concave flanges are to be formed, may draw upon the material at each end of the concave portion, and impart a fullness which increases slightly the linear measurement of the concave part. The surplus material thus created enables the concave flange to be turned without undue strain at any point, so that the integrity of the flanged bar is preserved and the weakness inseparable from the older methods of production is completely eliminated.

The punch of the drawing press will have a width equal to the distance between the dotted parallel curved lines 11¹ and 12¹, Fig. 3. The curved blank is laid over the matrix, and when the punch is actuated to press the blank into the matrix, the margins lying beyond the said dotted lines 11¹ and 12¹ will be folded against the opposite sides of the punch, as the latter is forced into the matrix. The lateral pressure exerted simultaneously by the side walls of the matrix upon the flanges and against the punch, will smooth out the crimps or corrugations as the punch and the blank enter the matrix. In some constructions of drawing presses, the side members of the matrix are capable of joint movement toward each other, to impart a set to the flanges of the bar as the punch completes the drawing operation. In presses of this type, such movement of the side members of the matrix, with the resultant lateral pressure, may be utilized to press out the crimps or corrugations in the concave flanges.

In the drawing operation, the convex portions of the margins will be shortened by reason of their being crowded into an arc of less length, and thus the material at these points will be slightly thickened. At the same time these convex portions will tend to elongate, and thus augment the concave portions by the addition of material which will be absorbed in the crimped or corrugated sections out of which the concave flanges are formed.

Having thus described my invention, what

I claim to secure by Letters Patent of the United States is:

1. The process of forming curved flanged bars from sheet metal plates, which consists in crimping the margins of a curved plate at points so as to provide a fullness to avoid stretching of the metal in producing the concave flanges, bending the side margins away from the plane of the plate to form the flanges of the bar, and eliminating the crimps by pressure upon the curved flanges.
2. The process of forming flat metal plates of curved outline into curved flanged bars, which consists in crimping the margins of the plate at the concaved portions to provide a fullness to avoid stretching the metal in producing the concave flanges, bending the side margins away from the plane of the plate to form the flanges of the bar, and eliminating the crimps by pressure.
3. The process of forming flat metal plates of curved outline into curved flanged bars, which consists in crimping the margins of the plate at the concaved portions to provide a fullness to avoid stretching the metal

in producing the concave flanges, and simultaneously bending the side margins away from the plane of the plate to form the flanges of the bar and eliminating the crimps by pressure applied during the flange bend- 30

35 4. The process of forming flat metal plates of curved outline into curved flanged bars, which consists in crimping the margins of the plate at the concaved portions to provide a fullness to avoid stretching the metal in producing the concave flanges, turning the side margins away from the plane of the plate and into parallel planes standing normal to the plane of the plate to form the 40 flanges, and simultaneously eliminating the crimps in both flanges by lateral pressure.

In testimony whereof, I have signed my name at Milwaukee, this 13th day of April, 1920.

R. STANLEY SMITH.
